UNITED STATES PATENT OFFICE.

DOMINGO ARAMBURU, OF WASHINGTON, DISTRICT OF COLUMBIA, ASSIGNOR TO SAMUEL FERRARI, OF NEW YORK, N. Y.

ADVERTISING MACHINE.

Application filed July 20, 1925. Serial No. 44,899.

This invention relates to an advertising device, and the object is to provide a plurality of individual signs or advertising units adapted to be moved successively by a continuously driven mechanism into position for observation, each unit thus brought to operative position being then moved rearwardly to inoperative position and another unit being brought into view.

10 A further object is to provide for the automatic movement of the curtain across the field of vision while the change of units is being made, and to provide for the automatic return of the curtain to inoperative position.

15 A further object is to provide particular and novel means for shifting the units.

20 A further object is to provide novel forms of advertising units, with means for illuminating the units individually, some of said units having movable figures thereon, and the provision being made for actuating the elements of the figures from common driving or actuating mechanism.

25 With the foregoing and other objects in view, the invention consists in the novel construction and arrangement of elements described, illustrated and claimed, it being understood that modifications may be made 30 within the scope of the claims without departing from the spirit of the invention.

In the drawings forming part of this application:

35 Figure 1 shows the housing of the device, and shows one of the movable advertising units in position for observation, the other advertising matter being in the nature of a permanent display, and the figure as a whole being a perspective view.

40 Figure 2 is a perspective view showing the mechanism for actuating the individual advertising units, several of these units being shown in dotted lines, those at the right being adapted for movement toward the observer, then to the left, and then in a direction from the observer, after which they are movable to the right, to stopping position.

45 Figure 3 is a perspective view showing the lower tracks and showing in the upper portion means for operating a curtain, and in the lower portion of the view, a portion of the actuating mechanism.

50 Figure 4 is a vertical section on line 4—4 of Figure 3.

Figure 5 is a section on line 5—5 of Figure 4.

Figure 6 is a perspective view of one of the advertising units, with means at the left side of the view for completing electric circuits, for illuminating purposes.

Figure 7 is a section on line 7—7 of Figure 6, the view showing independent means for illuminating the unit there illustrated, each of the units employed to be lighted by the particular lamps carried thereby.

Figure 8 is a view in front elevation showing an advertising unit employing movable elements.

Figure 9 constitutes a vertical section 70 through a unit of the type shown in Figure 8, the details of the actuating mechanism being illustrated.

Figure 10 is a view in front elevation showing another form of advertising unit 75 carrying movable elements.

Figure 11 is a diagrammatic view showing means for illuminating this unit and for actuating the movable elements.

Figure 12 is a view in front elevation 80 showing a still further form of unit.

Figure 13 constitutes a vertical section through a unit of the form of Figure 12, the actuating means being illustrated in detail.

Referring especially to Figure 2, several 85 advertising units are shown in dotted lines and are designated, respectively, 10, 11, 12 and 13, these units being, if desired, of the type illustrated in Figure 6, or carrying movable elements of the kind shown in certain other views of the drawings.

90 These units each include vertical outer elements such as 14 and 15, and an intermediate element 16, the devices 14, 15 and 16 being spaced about as shown in Figure 95 6, and as shown in horizontal section in Figure 7. Upper and lower transverse elements or plates 17 connect the several vertical elements, and anti-friction rollers 18 are mounted on vertical axial elements 19, 100 positioned in plates 17 in the manner illustrated especially in Figure 6. These anti-friction rollers engage the track structure shown in Figure 3, and serve to guide the advertising units into position. Each unit 105 carries a series of contact fingers, such as those shown at the left in Figure 6, wherein the fingers are designated 20 and project from one end of the unit and are adapted for engagement with stationary contact de- 110

vices 21. These contact fingers 20 complete circuits through elements 21, and thence through lamps such as those shown in dotted lines in Figure 6. The lamps 25 are mounted in individual compartments, as shown in Figure 7, the partitions for these compartments being designated 26, and it is the intention that a letter for each word of the sign, or for the word in the middle of the sign in Figure 6 shall be illuminated by a separate lamp, the lamps being lighted successively. In Figure 6 the upper and lower lines of the sign are each illuminated by a single lamp, these lamps being designated 30 and 31.

The track structure of Figure 3 includes the longitudinally extending elements 35, and the elements 36 extending perpendicularly with reference to members 35. Channels 37 provide for movement of the units in one direction longitudinally of the housing, and channels 38 provide for similar movement longitudinally of the housing in the other direction, while channels 39 and 40 provide for movement forwardly and rearwardly of the housing.

An electric motor is designated 45, and drives a shaft 46 carrying a worm 47 meshing with worm gear wheel 48, this gear wheel being mounted on shaft 49 carrying gear wheel 50. Gear wheel 50 meshes with gear wheel 51 on shaft 52, and the shaft last named carries a drum 53, the body portion of which is of insulation, the drum mounting a segmental metallic plate 55, the edge portion of which is cut away in the manner shown in Figure 2, in order to make successive contact with the spring fingers or contact devices 56, shown in the lower right hand portion of Figure 2. Wires such as 57 extend from contact fingers 56 and extend thence to contact fingers such as those shown at the left of Figure 2, whereby circuits are completed through the illuminating devices of the individual units.

A chain or endless device 60 is driven by wheel 61 mounted on shaft 52, this chain passing around sprocket wheel 63 on shaft 64, and passing thence around sprocket wheel 65 mounted at 66. The chain further passes over sprocket wheel 67 mounted at 68, continuing thence around sprocket wheel 61 before mentioned.

Shaft 64 mounts a sprocket wheel 69 driving chain 70 passing over sprocket wheel 71 on shaft 72, the latter carrying a gear wheel 73 adapted to mesh with a gear wheel such as 74 carried by any of the sign units, and adapted to actuate movable elements therein, assuming that the unit is thus provided.

In Figure 7 means for driving movable elements of one of the sign units are shown conventionally, the gear wheel 74 being mounted on shaft 75 and carrying sprocket wheel 76 driving chain 77 passing over

sprocket wheel 78 mounted as shown, that is, on a shaft 79 which also mounts a sprocket wheel 80 imparting movement to chain 81 passing over sprocket wheel 82 on shaft 83. This shaft last named carries a 70 pulley wheel or the like designated 84 and adapted to drive a belt or the like for imparting movement to any of the movable members of a sign unit, such, for instance, as the units illustrated in Figures 8 to 13. 75

Figure 1 shows a housing 5 provided with an observation opening or window 6 opposite which the sign units to be displayed are shifted. The right hand side of the housing carries a permanent display device 7 and the 80 sign units at the right of Figure 2 are assumed to be opposite this portion of the device, and, obviously, are not intended to be seen until they are shifted successively to position opposite opening 6 at the left of 85 Figure 1.

During the operation of shifting the units to position for observation, a curtain or the like, designated 85, is opposite the opening 6 of Figure 1, and the display matter is not 90 on exhibition during the shifting operation. This curtain 85 need not be flexible, but is rather of light rigid construction, and mounts rollers such as 86 on which the curtain is slidable over track 87. Upper guiding members are designated 88 and cooperate with the upper tracks or guides 89. The curtain 85 is thrown to inoperative position by means of a cord or cable 90 connected with the curtain at the point 91, this cord passing over idle pulley 92 and thence over pulley wheel 93 mounted on shaft 94, the shaft being adapted to be supported in suitable bearings, not shown. Rigid with pulley wheel 93 is a smaller pulley wheel 95 on 100 which cord 96 is wound, this cord being connected with a weight 97 constituting a gravity device by means of which the curtain is thrown to inoperative position, that is, moved to the right in Figure 3 when the 105 advertising matter is in position for exhibition.

The curtain 85 carries an arm or the like designated 98 having a slot therein, the slot being engaged by a pivoted latch 99. The pivotal point is shown at 99', and a stop 100 is mounted below latch 99 and limits the downward movement thereof. When the curtain is moved to the left of Figure 3 by means referred to below, arm or element 98 passes beneath the pivoted latch and raises the latter, permitting it to drop into the slot in arm 98 and secure the curtain in the position of Figure 3. During this movement the gravity device 97 will be lifted, and it will be understood that upon the release of latch 99, at the proper time, the curtain will automatically move to the right of Figure 3 by reason of the weight 97. The advertising units carry lugs or the like designated 101 110

positioned for engagement with the latch 99 at the point 99", and the downward movement of end portion 99" causes the release of the latch as the advertising unit comes 5 into display position.

In order to move the curtain to the left of Figure 3, chain 60 is provided with an engaging device or lug 60' for contact with projecting element 103 carried by the curtain. The movement of the upper run of chain 50 toward the left and the engagement between devices 60' and 103 produces the movement of the curtain to the position just mentioned, that is, to closed position.

15 Chain 60 further carries an engaging device 60^a, shown in Figure 2, and adapted for engagement with the lower corner portion of any of the sign units, for the purpose of moving one of these units from the right of Figure 2, to the left thereof, and into the 20 position of unit 10.

After unit 10 has been on display it is carried rearwardly by the movement of an engaging device 105, this element having the 25 general form of an angle bar and being adapted for engagement with one lower edge of unit 10. Each unit is provided with contact devices 106, with which the ears 107 of members 105 come into engagement for 30 shifting the unit as here indicated. Each device 105 is mounted rigidly on a vertical pin 108 passing through arm 109 extending radially from disk 110 mounted on a vertical shaft 111. A similar arm 112 is connected 35 with another sign unit engaging device 113, shown at the right of Figure 2. The pins 108 also pass through bars 114 movable forwardly and rearwardly of the housing between anti-friction rollers 115. This construction permits the shifting of the units at 40 the left of Figure 2 rearwardly of the housing, and simultaneously permits the shifting of the unit at the right of the housing to a forward position. The rotation of disk 110 by means of vertical shaft 111 produces the 45 shifting operation specified, and this rotation, or partial revolution, is produced by tension exerted on chain 125 connected with slidable element 126 operating in brackets or guides 127. Slide 126 carries an upwardly extending and offset portion 128 engaged by element 130 on chain 131 driven from sprocket wheel 132 on shaft 49. Chain 125 is connected with arm 109 at the point 109'. 50 A reverse movement of arms 109 and 112 by the rotation of shaft 11 is produced by means of arm 116 connected at 117 with shaft 111. Arm 116 is movable across plate 118 and is engaged by a contact device or 55 devices 120 carried by chain 60.

Figure 5 shows a horizontal section on line 5-5 of Figure 4, and shows vertical shaft 111 in section and arm 116 in top plan. A guard member 135 is also shown in section and is further shown in Figure 3 in perspec-

tive. In this view chain 60 passes between guard members 136.

Advertising unit 10 of Figure 2 having been moved rearwardly, it is then movable to the position of unit 11, and the latter is 70 carried backward and is then in position to be shifted to the position of unit 12, and thereafter to the position of unit 13. It will next come to the front, at the right of Figure 2 and will then be in position to be carried to the left, and to the position of unit 10 of Figure 2. The movement longitudinally of the housing, at the rear of Figure 2, is effected by means of the other chain 131 which will carry an engaging device similar 75 to device 60^a of chain 60.

When the advertising units are in display position, the electric lamps, such as 25, 30 and 31 of Figure 6, will be lighted. Contact fingers 20 at the left of Figure 6 come into 85 engagement with contact devices 21 and a circuit is completed through the metallic plate 55 in the lower right hand portion of Figure 2. The edge portion of this plate is staggered as shown, or other arrangement 90 may be made for completing individual circuits, and lighting individual lamps, successively.

Referring to Figure 2, it may be assumed that current flows from point 140, at the left 95 of the view, through wire or one wire 57 to one of the brushes 56, and thence to contact plate 55. Brushes or fingers 56 are in engagement with this plate and are in electric contact with wires 57, leading to the individual 100 contact devices 21 of Figure 6 and thence through contact fingers 20 and wires 20' to the lamps of the sign, the circuit being completed through a common return wire 141 connected with contact finger 142 which engages contact member 143 connected with the negative side of the supply circuit. The individual signs are thus illuminated as they are brought to operative position, and where these units carry movable elements such as 110 those shown in Figures 8 to 13, the movable elements of the signs will be operated, due to engagement between gear wheels 74 of the units and gear wheels 73 of the actuating mechanism. The gear wheels last named are 115 shown in the lower left hand corner of Figures 2 and 3.

In Figures 8 and 9 one form of advertising unit bears the representation of a man in the act of shaving, and the movable elements 120 include the hand 150 holding the razor, and the eyelids and eyebrows.

Gear wheel 74 is mounted on a shaft 74' carrying a sprocket wheel 151 driving chain 152 passing over sprocket wheel 153 on shaft 125 154 also carrying a sprocket wheel driving chain 155 and a sprocket wheel driving chain 156. Chain 156 drives mechanism actuating chain 157 imparting movement through a sprocket wheel 158 to shaft 159 130

mounting an eccentric member 160. This member imparts movement to rod 161 pivotally connected with an element 163 pivoted at 164 and operating a portion 165 representing an eyelid. A similar eyelid 166 is operated by bar or arm 167 and rod 162 pivoted to rod 161.

Chain 155 imparts movement through suitable mechanism to chain 168 carrying an engaging device 169 which contacts with arms such as 170 of eyebrow members 171 held in normal position by springs 172.

The hand 150 carrying the razor is mounted on a vertically slidable element 174 guided in slot 175. Movement is imparted to slide 174 by means of a cord 176 connected with slide 177 engaged by lug 178 on chain 157. A similar slide 177' may be connected with the brush 177^a of Figure 8, and is operatively connected with element 174. Slide 177' is provided with a lug (with which lug 169 may also cooperate), for reversing the movement of element 174. Any of the units may be illuminated as illustrated elsewhere, and it is not necessary to describe lighting means in this immediate connection.

Figures 10 and 11 show another form of unit, wherein a figure representing a shoemaker includes elements automatically operative for handling the thread in the operation of sewing a shoe. The driving wheel is designated 74, as in the previous instance, and without describing every element of the drive, it will be understood that movement is imparted through chains 180 and 181 to shaft 182 mounting an eccentric member 183 cooperating with eccentric strap 184 and connected with a flexible device 185. The latter moves vertically and has connected therewith threads or the like designated 186 which diverge and have their upper and outer ends connected with the hands 187 of the shoemaker represented by the movable figure. The arms of the figure include the elements 188 and 189, and these elements are connected with mechanical arms 190 held by springs such as 191, so that the arms of the shoemaker when drawn toward each other by means of tension on cord 185 will be turned to normal or original position under the action of springs 191. Another movable element of the sign designated 192 may be operated on shaft 193 constituting an obvious portion of the driving mechanism.

A further form of movable advertising unit is shown in Figures 12 and 13, wherein the figures permanently carried by the display member are designated 195, 196, and 197. The front of the advertising unit is provided with a surface which may be termed a blackboard, this being shown at 198 and being provided with a window 199 through which the display member 200 is

visible. Several of these display members or figures are carried by a disk 201 rotatable on a shaft 202, and as an individual element comes into position opposite window 199 the hand 201 of the figure shown at 197 is removed for the purpose of attracting attention.

The figure shown at 195 is then expected to indicate the character of the display member 200, and it is assumed that whereas 75 a triangle is on exhibition, it will be termed a square by the figure shown at 195. This operation is produced by means of disk 204 carrying several words, such as Angle, Square and Circle, and when disk 204 is in 80 the position of Figure 12 the word Square will be visible and it is assumed that the figure shown at 195 has applied the term Square to the triangle on display. Disk 204 may be assumed to be driven from one 85 of the chains illustrated in Figure 13 and designated 205 and 206, chain 206 driving through suitable means an eccentric device 207 imparting movement to rod or cord 208 for operating lever 209 which imparts movement to hand 201. The jaw of figure 197 is designated 210 and is operated by element 211. It will be understood that chain 205 is driven from one of the standard gear wheels, such as wheel 74 at the lower left 95 hand corner of the view. A further disk 212 carries several words in the nature of comments on the term applied by figure 195 to the display element. Figure 12 shows that the comment made by the individual represented by 196 is Foolish, indicating that the figure 195 has made an absurd error. Disks 201, 204, 212 have rigidly connected therewith, wheels such as 201' engaged and rotated by chain 206. It 100 is obvious that display devices of this type may be produced in a great variety of forms, and those described and illustrated are merely by way of example.

Having thus described the invention, what 110 is claimed as new is:—

1. In a device of the class described, a plurality of independent advertising units having movable elements thereon, means carried by each unit for driving said movable elements, continuous traveling means movable longitudinally and separate rotatable means intermittently operable, for moving these units into and out of display position, and means automatically engaged when the units are moved to display position for actuating the driving means within the independent units.

2. In a device of the class described, a plurality of independent advertising units 125 having movable elements thereon, means carried by each unit for driving said movable elements, continuous traveling means movable longitudinally and separate rotatable means intermittently operable for mov- 130

- ing these units into and out of display position, means automatically engaged when the units are moved to display position for actuating the driving means within the independent units, a curtain for shielding the advertising units while being moved to display position, and means for moving the curtain from operative to inoperative position.
10. 3. In a device of the class described, a plurality of independent advertising units having movable elements thereon, means carried by each unit for driving said movable elements, continuous traveling means movable longitudinally and separate rotatable means intermittently operable for moving these units into and out of display position, means automatically engaged when the units are moved to display position for actuating the driving means within the independent units, a curtain for shielding the advertising units while being moved to display position, means for moving the curtain from operative to inoperative position, and devices for automatically releasing the means last named when a unit comes into display position.
4. In a device of the class described, a plurality of independent advertising units having movable elements thereon, means carried by each unit for driving said movable elements, continuous traveling means movable longitudinally and separate rotatable means intermittently operable for moving these units into and out of display position, means automatically engaged when the units are moved to display position for actuating the driving means within the independent units, illuminating means for the individual advertising units, and means for automatically making electric contact for the illuminating means when the units come into display position.
5. In a device of the class described, a plurality of independent advertising units having movable elements thereon, means carried by each unit for actuating said movable elements, means automatically engaged at intervals for imparting motion to the actuating means of the independent units, a housing having a display opening on one side thereof, a curtain for closing the opening, means for retaining the curtain temporarily in closed position, means for shifting the curtain to open position when the retaining means are released, and continuous traveling means movable longitudinally and separate rotatable means actuated by the traveling means and intermittently operable for shifting the advertising units into and out of display position and effecting the automatic release of the curtain by said shifting operation.
6. In a device of the class described, a plurality of advertising units having mov-
- able elements thereon, means carried by each unit for actuating said movable elements, means automatically engaged at intervals for imparting motion to the actuating means of the independent units, a housing having a display window on one side of the front portion thereof, means for shifting the units successively to position opposite the opening, means for carrying said units rearwardly from the opening after display, 75 means for moving the units longitudinally of the housing, at the rear portion thereof, and means for successively carrying the units forwardly on the side of the housing opposite the display opening, said means last named including a rotatable device separate from and intermittently operable by the means for moving the units longitudinally.
7. In a device of the class described, a plurality of advertising units having movable elements thereon, means carried by each unit for actuating said movable elements, means automatically engaged at intervals for imparting motion to the actuating means of the independent units, a housing having a display window on one side of the front portion thereof, means for shifting the units successively to position opposite the opening, means for carrying said units rearwardly 95 from the opening after display, means for moving the units longitudinally of the housing, at the rear portion thereof, means for successively carrying the units forwardly on the side of the housing opposite the display opening, said means for moving the units rearwardly and forwardly including radial elements simultaneously engaging opposite units in reverse directions and rotatable intermittently by the means, continuously movable, for shifting the units longitudinally of the housing, and a curtain for closing the window in timed relation with the operation of the means for moving the units.
8. In a device of the class described, a plurality of advertising units having movable elements thereon, means carried by each unit for actuating said movable elements, means automatically engaged at intervals for imparting motion to the actuating means of the independent units, a housing having a display window on one side of the front portion thereof, means for shifting the units successively to position opposite the opening, means for carrying said units rearwardly from the opening after display, 115 means for moving the units longitudinally of the housing, at the rear portion thereof, means for successively carrying the units forwardly on the side of the housing opposite the display opening, said means for moving the units rearwardly and forwardly including radial elements simultaneously 120 engaging opposite units in reverse directions.

and rotatable intermittently by the means, continuously movable, for shifting the units longitudinally of the housing, and a curtain for automatically closing the window in timed relation with the operation of the means for moving the units.

9. In a device of the class described, means for shifting a plurality of advertising units into and out of display position in a housing, said means including a plurality of travelling elements movable in opposite directions, engaging devices on said elements, and a plurality of arms and mounting means therefor rotatable about a common axis, said arms engaging the units from opposite sides and moving them in parallel paths in opposite directions, and the travelling elements being movable perpendicularly of said paths of travel.

10. 10. In a device of the class described, means for shifting a plurality of advertising units into and out of display position in a housing, said means including a plurality of travelling elements movable in opposite

directions, engaging devices on said elements, and a plurality of arms and mounting means therefor rotatable about a common axis, said arms engaging the units from opposite sides and moving them in parallel paths in opposite directions, the travelling elements being movable perpendicularly of said paths of travel, and automatically operated means for shielding the units while being moved into display position.

11. A plurality of movable display units for an advertising device, said units comprising frames bodily movable independently of each other, unitary power driving mechanism, said units carrying permanent display matter and including movable elements cooperating with the display matter, mechanical means for actuating the movable elements and including a gear wheel mounted near an edge portion of each unit, adapted to be engaged and driven by the power mechanism.

In testimony whereof I affix my signature.
DOMINGO ARAMBURU.
